(57) **CLAIM**

The ornamental design for "wall and ceiling speaker bracket," as shown.

DESCRIPTION

FIG. 1 is an upper front side perspective view of a first embodiment showing my new design;

FIG. 2 is a top view of the first embodiment showing my new design;

FIG. 3 is a rear view of the first embodiment showing my new design;

FIG. 4 is a left side view of the first embodiment showing my new design;

FIG. 5 is a front view of the first embodiment showing my new design;

FIG. 6 is a right side view of the first embodiment showing my new design;

FIG. 7 is a bottom view of the first embodiment showing my new design;

FIG. 8 is an upper front side perspective of a second embodiment showing my new design;

FIG. 9 is a top view of the second embodiment showing my new design;

FIG. 10 is a rear view of the second embodiment showing my new design;

FIG. 11 is a left side view of second embodiment showing my new design;

FIG. 12 is a front view of the second embodiment showing my new design;

FIG. 13 is a right side view of the second embodiment showing my new design; and,

FIG. 14 is a bottom view of the second embodiment showing my new design.
